UNITED STATES PATENT OFFICE.

ALBERT F. ROBBINS, OF WALTHAM, MASSACHUSETTS.

DEVICE FOR TIGHTENING PENDANT BOWS OF WATCHES.

Application filed September 30, 1922. Serial No. 591,506.

To all whom it may concern:

Be it known that I, ALBERT F. ROBBINS, a citizen of the United States, residing at Waltham, in the county of Middlesex and State of Massachusetts, have invented new and useful Improvements in Devices for Tightening Pendant Bows of Watches, of which the following is a specification.

This invention relates to a device for
10 tightening pendant bows of watches and
has for its object to provide a device of sim-
ple construction particularly adapted to
support and position the pendant bow of a
watch and also force the opposite extremi-
15 ties of said bow into the openings provided
therefor in the pendant of said watch.

The invention consists in the combination and arrangement of parts set forth in the following specification and particularly 20 pointed out in the claims thereof.

Referring to the drawings:

Figure 1 is a front elevation of a device embodying the invention, a watch being illustrated in connection therewith, and

25 Fig. 2 is a central vertical section partly in elevation taken on the line 2—2 of Fig. 1.

Like numerals refer to like parts throughout the several views of the drawings.

In the drawings, 5 represents a casing or
30 a watch from which projects a pendant 6
which is fastened to said casing in any suit-
able manner. A bow 7 of suitable design is
pivotaly mounted upon the pendant 6 and
said bow is provided with ears 8 formed inte-
35 gral therewith at the opposite extremities
thereof which project into oppositely dis-
posed openings 9 provided in said pendant.
A stem 10 extends from the interior of the
casing 5 through the pendant 6 and has a
40 crown 11 rigidly fastened thereto at the
outer end thereof in the usual well known
manner.

45 It is not customary in constructing watches to provide any means for positively holding the ears 8 of the bow 7 within the openings 9 of the pendant 6 and it is, therefore, necessary to rely entirely upon the strength of the material of which said bow is constructed to prevent the opposite extremities thereof from spreading and thereby becoming detached from said pendant. It is, therefore, important that when the watch is first constructed and at all times thereafter that the extremities or ears 8 shall be tight within their respective openings. It has been customary heretofore in

applying the bow to the pendant and at such times thereafter that it is necessary to tighten said bow to employ pinchers but instruments of this character are unsatisfactory and there is considerable danger of defacing and marring the watch when they are used.

The device of this invention is provided for the special purpose of forcing the extremities of the bow into the openings provided therefor in the pendant of the watch in a practical and easy manner and without danger of in any way marring the portions of the article with which it is brought in contact and is as follows:—A bifurcated member 12 is provided with furcations 13 at the outer extremities of which are provided notches 14. Slidably mounted within an opening 15 in the member 12 and projecting a short distance outwardly therefrom at a point intermediate the furcations 13 is a member 16 and the latter is shouldered at 17 to provide a reduced portion 18. A spring 19 surrounds the reduced portion 18 of the sliding member 16 within the opening 15, one end of said spring bearing against the shoulder 17 of the member 16 and the other end of said spring bearing against a shoulder 20 formed within the 85

against a shoulder 20 formed within the member 12. The reduced portion 18 of the member 16 has screw-threads provided thereon which engage similar screw threads formed within a bushing 21, the latter being rigidly secured in any suitable manner within an opening 22 provided within a handle 23. A support 24 constructed in the form of a hook is provided with a screw-threaded portion 25 which has engagement with the sliding member 16 and the position of the hooked portion of the support 24 relatively to the outer extremity of the sliding member 16 is adjusted by rotating said support in the proper direction within said sliding member 16. The support 24 is provided for the purpose of engaging the bow 7 as illustrated in the drawings and thereby holding the watch in a position to be engaged by the furcations 13 and it will be noted that when the watch is correctly positioned with relation to the device, that the longitudinal median line of the stem 10, crown 11, support 24, sliding member 16 and handle 23 are all coincident.

The general operation of the device is as follows:—Assuming that the bow 7 of the watch has become loosened within the pend-

ant 6 or, in other words, that the extremities of the ears 8 of said bow have spread and are not in contact with the bottom of the openings 9 provided therefor in said pendant, the bow is placed upon the hook portion of the support 24 and the handle 23 is then rotated in the proper direction to draw the sliding member 16 toward said handle within the bifurcated member 12 until the portions of the bow upon opposite sides of the support 24 are brought into the notches 14 and contact with the portion of the furcations 13 at the bottom of said notches. The bow 7 is now correctly positioned, and by still further rotating the handle 23 in the same direction as formerly, pressure will be applied upon said bow which will tend to force the opposite extremities of said bow inwardly toward each other until said extremities finally contact tightly with the bottom of the openings 9. The watch is then released by rotating the handle 23 in a reverse direction until it is possible to remove the bow 7 of the watch from the support 24. With this device, the bow is tightened very quickly and efficiently without any danger of in any way marring the surface of the bow and without danger of the device becoming accidentally detached from the bow during the tightening operation and contacting with the highly polished surface of the watch casing 5.

I claim:

1. A device of the character described comprising, in combination, a support for a pendant bow, a bifurcated member adapted to engage said bow upon opposite sides of said support to position said bow relatively to said support, means to normally force said support and bifurcated member in opposite directions, and means to move said support relatively to said positioning means to force the extremity of said bow in opposite directions.

2. A device of the character described comprising, in combination, a support for a pendant bow, a bifurcated member adapted to slide relatively to said support and engage said bow upon opposite sides of said support to position said bow relatively to said support, a yielding member interposed between said bow support and said bifurcated member and normally forcing the same in opposite directions, and means also to move said support relatively to said positioning means to force the extremities of said bow toward each other.

3. A device of the character described comprising, in combination, a support for a pendant bow, a bifurcated member provided with notches formed therein to receive said bow and adapted to slide relatively to said support and engage said bow upon

opposite sides of said support to position said bow relatively to said support, a spring interposed between said support and said bifurcated member, and means also to move said support relatively to said positioning means to force the extremities of said bow toward each other.

4. A device of the character described comprising, in combination, a support for a pendant bow, a bifurcated member provided with notches formed therein to receive said bow and adapted to engage said bow upon opposite sides of said support to position said bow relatively to said support, a member slidably mounted within said bifurcated member and operatively connected to said bow support and means engaging said slideable member and adapted to move the latter together with said bow support relatively to said bifurcated member to force the extremities of said bow toward each other.

5. A device of the character described comprising, in combination, a support for a pendant bow, a bifurcated member provided with notches formed therein to receive said bow and adapted to engage said bow upon opposite sides of said support to position said bow relatively to said support, a member slidably mounted within said bifurcated member and having screw-threaded engagement with said bow support and a handle having screw-threaded engagement with said slideable member and adapted to be rotated to move the latter together with said bow support relatively to said bifurcated member to force the extremities of said bow toward each other.

6. A device of the character described comprising, in combination, a support for a pendant bow, a bifurcated member provided with notches formed therein to receive said bow and adapted to engage said bow upon opposite sides of said support to position said bow relatively to said support, a member slidably mounted within said bifurcated member and operatively connected to said bow support, a spring interposed between said slideable member and said bifurcated member and a handle having screw-threaded engagement with said slideable member and adapted to be rotated to move the latter together with said bow support relatively to said bifurcated member to force the extremities of said bow toward each other.

In testimony whereof I have hereunto set my hand in presence of two subscribing witnesses.

ALBERT F. ROBBINS.
